(57) **CLAIM**

The ornamental design for an arrowhead, as shown and described.

DESCRIPTION

A portion of the disclosure of this patent document contains material which is subject to copyright protection. The copyright owner has no objection to the facsimile reproduction by anyone of the patent disclosure, as it appears in the Patent and Trademark Office patent files or records, but otherwise reserves all copyright rights whatsoever.

FIG. 1 is a front elevation view of the arrowhead.

FIG. 2 is a rear elevation view of the arrowhead.

FIG. 3 is a left side elevation view of the arrowhead.

FIG. 4 is a right side elevation view of the arrowhead.

FIG. 5 is a top view of the arrowhead.

FIG. 6 is a bottom view of the arrowhead.

FIG. 7 is a right front isometric view of the arrowhead; and, FIG. 8 is a right rear isometric view of the arrowhead.

The dashed, broken lines in the drawings illustrate portions of the arrowhead that form no part of the claimed design. The dot-dash, broken lines in the drawings define the bounds of the claimed design and form no part of the claimed design.
